BENDING TOOL

Samuel Austin, 36 Colebrook St., Hartford 12, Conn.

Filed Apr. 10, 1959, Ser. No. 805,538

15 Claims. (Cl. 1—222)

The present invention relates to hand tools of the pliers type adapted to effect a bending operation; and is more particularly concerned with an improved tool for wrapping a metal clip about a bundle of wires or the like simply, quickly and automatically.

In various assembly operations known at the present time, it is often desired to secure a bundle of wires or the like to one another, or to otherwise fasten two elements together. In wire bundling operations, e.g. the binding of a plurality of loose, insulated electric wires such as is commonly done in neon sign wiring, electronics, telephone and similar applications, it has been the practice in the past to hand tape such a plurality of wires to one another. This procedure, which is tedious and often unsatisfactory from a structural point of view, has been supplanted in some instances by clipping operations wherein a metal band is placed about the bundle of wires to produce a unitary multiconductor cable; but these clipping operations have in general been characterized by the crimping of a metal band about such a bundle of wires, with the attendant possibility of rupturing the insulation of said wires; or in the alternative, have been characterized by the provision of a clip having a butt joint (such as will be described hereinafter) which has little mechanical strength.

It has been recognized that the best form of clip which can be employed for bundling a group of conductors to one another takes the form of a wrapped metal clip, i.e. one in which the free ends of the clip overlap one another, in a manner analogous to the plural tape wraps mentioned previously. Such wrapped clips, however, have not been widely employed heretofore inasmuch as the wrapping operation has necessarily had to be manual; and no tools have been available to expedite this manual clip wrapping technique. In particular, it will be appreciated that conventional pliers type tools are so constructed that the jaws thereof approach a center line together as the tool is actuated, whereby any attempt to use a conventional pliers in clip bending operations necessarily prevents a wrapped clip from being formed since the proximity of the two jaws makes it impossible for one portion of a clip to be bent in overlying relation to another portion of that same clip.

The present invention, recognizing these deficiencies of conventional tools suggested heretofore as well as disadvantages of taping, crimping and clipping operations utilized in the past, is particularly concerned with a novel pliers type tool adapted to effect a true wrapping of a metal clip about a bundle of wires or the like. In this respect, therefore, the present invention is concerned with a pliers type tool having bending jaws and an associated mechanism so arranged that, upon actuation of the tool, one bending jaw is adapted to effect a bending operation and thereafter move out of the way to permit a subsequent bending operation by the other bending jaw of the tool. By using this tool, therefore, one seeking to produce a clipped bundle of wires can do so by a simple hand operation comprising a single squeezing

2

together of the tool handles; and this simple motion of the tool handles automatically produces a more complex motion of the tool bending jaws whereby said bending jaws operate in proper sequence to effect a clip bending and wrapping operation.

It is accordingly an object of the present invention to provide an improved bending tool of the pliers type.

Another object of the present invention resides in the provision of a hand tool adapted to produce a wrapped 10 clip about a bundle of wires or the like.

Another object of the present invention resides in the provision of a pliers type tool so arranged that the jaws thereof approach a work location in sequence rather than simultaneously.

Still another object of the present invention resides in the provision of a pliers type tool having a pair of bending jaws so arranged and operated that one jaw is adapted to effect a bending operation at a work location whereafter that one jaw is adapted to move away from the work location to permit a subsequent bending operation by the other jaw without interference from the first mentioned jaw.

Still another object of the present invention resides in the provision of a hand tool and associated linkage 25 adapted to effect a reciprocating motion of at least one bending jaw on said tool, as said tool is actuated.

A further object of the present invention resides in the provision of a tool adapted to wrap a clip more quickly and efficiently than has been possible heretofore.

A still further object of the present invention resides 30 in the provision of a hand tool designed to expedite the bundling of wires and designed to permit the bundling of various different numbers of wires at the election of the tool user.

In providing for the foregoing objects and advantages, the present invention contemplates the provision of a pliers type tool comprising a pair of operating handles cross-connected to one another at a pivot point located intermediate the ends of said handles, whereby the 35 squeezing of the handles toward one another about said pivot point, on one side of said pivot point, effects a similar motion of the operating portions of said handles located on the other side of said pivot point. Indeed, this form of mechanical motion is well known and is characteristic of conventional pliers suggested heretofore; and it must therefore be understood that this form of structure and mechanical motion is contemplated in the subsequent description and appended claims whenever the term "pliers type" tool is utilized.

In ordinary pliers type tools, however, it is usual for the jaws thereof to approach one another at a common rate. In distinction to this, the present invention contemplates the provision of a pair of jaws on said tool which approach a work location at different rates and 50 at different times whereby one bending jaw may effect an initial bending operation, followed at a later time by a subsequent bending operation effected by the other bending jaw. In providing for this operation, the tool of the present invention employs a movable bending jaw on one of the operating handles mentioned previously, 55 associated with a linkage so arranged that as the handles of the pliers type tool are squeezed together, the said movable bending jaw is caused to quickly move to a work location at a time when the other bending jaw is relatively remote from said work location, whereafter said movable bending jaw moves away from that work location as the other bending jaw moves into the work location. The work location in particular can comprise a socket forming a unitary portion of the tool adapted 60 to receive a clip and bundle of wires, or any other structure to be bent by the tool.

The foregoing objects, advantages, construction and

operation of the present invention will become more readily apparent from the subsequent description and accompanying drawings, in which:

Figure 1A illustrates an unbent clip of the type which may be employed in association with the tool of the present invention.

Figures 1B and 1C illustrate clips which may be formed from the structure of Figure 1A, with Figure 1B being particularly illustrative of an undesired form of bent clip, while Figure 1C is illustrative of the desired form of wrapped clip produced by the tool of the present invention.

Figures 2A through 2C inclusive illustrate the improved pliers type tool of the present invention in successive operation.

Figure 3 is a view of the tool of the present invention taken on the side thereof reverse to the side shown in Figure 2A.

Figure 4 is a detail view of a portion of the tool taken on line 4-4 of Figure 3; and

Figure 5 is a further detail view of a portion of the tool taken on line 5-5 of Figure 3.

Referring now to the several figures, it will be seen that, in order to produce a bundle of wires, a clip such as 10 (Figure 1A) may be employed. This clip may, if desired, be of substantially U-shaped configuration initially, may comprise a relatively soft metal such as aluminum, and may have legs which are of the same or different lengths depending upon the degree of wrapping desired in the final clip. It should further be noted that the metal clip shown in Figure 1A, and discussed hereinafter, may have appropriate insulation thereon where an insulated clip is desired or required, or may be fabricated of suitable flexible materials including insulating materials. The term "clip" used hereinafter, and in the appended claims, is therefore meant to include all of these various structures.

In a clipping operation, the bundle of wires to be secured to one another can be placed between the legs of the U-shaped clip 10, whereafter the free ends 10a and 10b of said clip can be bent toward one another to enclose the wires or the other structures to be secured. It will be appreciated that the bending operation described with regard to free ends 10a and 10b may be such as to produce a butt type joint (or indeed a crimped joint); and such a butt type joint, which has been conventional heretofore, is in fact illustrated in Figure 1B.

In particular, it will be noted that the free ends 10a and 10b of the clip shown in Figure 1B are disposed closely adjacent to one another along a line 11 rather than being in overlapping relation to one another; and such a butt type joint has been found in practice to have little inherent strength whereby any stress placed on the individual wires of a bundle retained by a clip such as that shown in Figure 1B causes a ready separation of the clip along the line 11, with the resultant considerable possibility that the wires will spread apart from one another, and indeed disengage from the required or desired bundle.

It should be noted that while the line 11 shown in Figure 1B has been illustrated as a substantially straight line, butt type joints of the types intended to be illustrated by Figure 1B can in fact take other forms, whereby the two portions of the clip interleave one another along a crenelated zigzag, or other irregular line; but, in all such instances, the characteristics of the butt type joint are nevertheless present, i.e. the facing portions of the clip are merely juxtaposed to one another rather than overlapping one another.

The form of clip most desired is that shown in Figure 1C; and this particular clip may retain a bundle of wires 12 in a cable or assembled arrangement by a clip having the free ends 10a and 10b physically overlapping one another along a surface 13. It is the prime purpose of

the present invention to form a clip of the type shown in Figure 1C inasmuch as this sort of clip, which is effectively wrapped about the wires, exhibits the wrapped strength which has been associated heretofore with conventional taping operations wherein a length of tape is wrapped in successive layers about a bundle of wires. The present invention, however, and the tool to be described hereinafter, effects such a wrapped clip quickly and automatically by a simple hand operation whereby the clip, of the type shown in Figure 1C, can be formed in a small fraction of the time normally required for hand taping.

It will be appreciated that a wrapped clip of the type shown in Figure 1C cannot be formed by conventional pliers type tools. In particular, if a clip of the type shown in Figure 1A were to be placed between the jaws of a conventional pliers type tool and those jaws were then caused to move toward one another, this movement is ordinarily such that the jaws approach one another at the same time. The resulting clip must therefore necessarily have either a crimped configuration or a butt joint of the type shown generally in Figure 1B. In order for a wrapped joint of the type shown in Figure 1C to be formed, however, the bending operation must be sequential in nature whereby one free end of the clip, e.g. end 10a, is first bent over the bundle of wires or the like, whereafter the second free end 10b of said clip is bent in overlying relation to the first bent end. Moreover, it will be appreciated that a simple sequential operation of the bending jaws is ordinarily not enough, since a jaw bending a free end such as 10a and thereafter remaining in place would tend to interfere with a later bending operation by another jaw seeking to bend free end 10b. Accordingly, a particular form of sequential operation is preferred, in that one bending jaw must bend a first portion of the clip and then move out of the way to permit a subsequent bending operation of another portion of the clip. These characteristic operations and motions are produced by the tool of the present invention; and this structure and functioning of said tool will become more readily apparent by reference to Figures 2 through 5 inclusive.

Referring now to the several Figures 2 through 5, it will be noted that the pliers type tool of the present invention may comprise a pair of operating handles 15 and 16 cross-connected to one another at a pivot 17 located between the ends of said handles. The handle 16 extends beyond the pivot 17 as an elongated arm 18 having a unitary bending jaw 19 extending therefrom. The jaw 19 is, as illustrated, of elongated configuration extending transverse to the direction of elongation of arm 18, wherefore the nose 20 and underside 21 of said jaw 19 can bend one portion of a clip, e.g. one of the legs of the clip shown in Figure 1A.

The other handle 15 extends beyond pivot point 17 and takes the form of an enlarged block or head 22 having a U-shaped depression 23 therein acting as a work location or socket adapted to receive a clip such as 10 and a bundle of wires such as 12 for the bending operations described previously. A portion of the head 22 may, if desired, include an auxiliary member, as at 23a, partially sawed through and hardened, whereby one side of depression or socket 23 comprises a member bent slightly inward and acting as a flat spring adapted to hold the clip 10 in socket 23 under light pressure. A spring 24 is disposed between the arm 18 and head 22 to normally hold the tool portions in the relative positions shown in Figure 2A; and it will be appreciated that operation of the tool, comprising a depression or squeezing of handles 15 and 16 toward one another about pivot point 17, will cause a compression of spring 24 whereby, upon release of the handles 15 and 16, the tool handles will spring apart to permit another clipping operation.

The head 22 does not, per se, act as a bending jaw in the tool. Instead a bending jaw 25 bolted by bolts 26 to a channel shaped bracket 27 is provided; and said channel shaped bracket 27 extends along both sides of head 22 (see Figures 2A, 3 and 4) and is pivotally attached to said head 22 by a pivot 28. It will be noted therefore that upon pivoting of bracket 27 about pivot 28, the bending jaw 25 can be pivoted into and out of locations adjacent the uppermost portion of socket 23; and this mounting of bending jaw 25 therefore permits said bending jaw to describe a reciprocating motion with regard to socket 23, in the manner to be discussed more fully hereinafter.

Under normal conditions, the bracket 27 is maintained in such position that the bending jaw 25 is disposed to one side of the open end of socket 23 (see Figure 2A); and in particular, a spring 29 is disposed between bracket 27 and arm 22 to urge bending jaw 25 away from socket 23, with the rest position of jaw 25 being limited by a pin 30 extending outwardly from head 22 and engaging an outer flat edge of bracket 27 at a position below pivot 28, as illustrated. In order to provide a desired motion of bending jaw 25, upon simple movement or squeezing of handles 15 and 16 toward one another, the bracket 27 includes an operating arm 31 extending downwardly, as illustrated; and this operating arm may comprise an integral portion of bracket 27, or may in the alternative comprise an extending arm fastened thereto, whereby forces applied to the lower end of arm 31 tend to pivot bracket 27 about pivot 28 against the restraint of spring 29 thereby to move bending jaw 25 into a position overlying the top of socket 23.

This movement of bracket 27, through the agency of arm 31, about pivot point 28 is effected by a linkage 32. In particular, said linkage 32 comprises a substantially L-shaped arm pivoted at a point 33 to arm 18, comprising the extension of handle 16. Arm or linkage 32 is normally urged in a clockwise direction about said pivot point 33 by a spring wire 34 fastened to the uppermost portion of arm 18 by means such as a nut and bolt 35, and engaging the L-shaped linkage 32 adjacent a lower portion thereof below pin 33, this arrangement being particularly shown in Figures 2A-C and 5. The clockwise rotation of linkage 32 is limited by a further pin 36 extending outwardly from arm 31 adjacent the lower portion thereof, and engaging a surface 37 formed as a cut-out portion at the free end of linkage 32. The linkage 32 further includes a latching surface 38 extending upwardly from surface 37 adjacent said free end and adapted to engage pin 36 in the manner to be described; and the upper portion of linkage 32 describes a curved cam surface 39 adapted to cooperate with still a further pin 40, extending outwardly from head 22 in the manner to be described.

The actual operation of the tool shown in Figures 2 through 5 will become more readily apparent by a consideration of Figures 2A, 2B and 2C in sequence. Figure 2A illustrates the tool in a non-operating position, i.e. prior to a desired clipping operation. In this position of the tool, the handles 15 and 16 are maintained in separated relation to one another by spring 24, and the bending jaw 25 is held away from socket 23 by spring 29. The socket 23 is therefore open and a clip such as 10 containing a bundle of wires such as 12 may then be inserted into the socket 23 for a clipping operation.

In order to produce the clip shown in Figure 1C, the handles 15 and 16 are depressed in a continuous motion toward one another, i.e. in a conventional pliers type action. Figure 2B depicts the tool operation as the handles 15 and 16 are partially depressed toward one another. In particular, as the tool is manipulated from the condition shown in Figure 2A to that shown in Figure 2B, the arm 18 and head 22 are caused to approach

one another. This relative motion between arm 18 and head 22 causes the latching surface 38 of linkage 32 to engage pin 36 on arm 31, and to be held in engagement therewith due to spring wire 34, whereby, as the handles 15 and 16 are moved toward one another, surface 38 bearing upon pin 36 causes bracket 27 to pivot in a clockwise direction about pivot 28. As this operation proceeds, the arm 31 is of course moved away from stop pin 30 and the bending jaw 25 is rapidly moved into a position wherein it engages one side or leg of the clip 10 adjacent thereto and bends that side of clip 10 over the top of the bundle of wires 12, as shown in Figure 2B. It will be noted that during this bending operation by bending jaw 25, the other bending jaw 19 is still relatively remote from socket 23.

In the initial portions of the operation depicted in Figure 2B, the pin 36 is located closely adjacent the junction of surfaces 37 and 38 on linkage 32. The upper cam surface 39 of said linkage 32 rides however upon pin 40 extending outward from head 22. Accordingly, as operating handles 15 and 16 are moved closer and closer to one another, the pin 40 forces linkage 32 downward about its pivot point 33 against the restraint of spring wire 34. As a result, latching surface 38 describes a downward sliding movement on pin 36 at the same time that it is engaging said pin to cause the pivotal motion of bracket 27 and bending arm 25, already described. At the time that bracket 27 is pivoted in a clockwise direction to the full extent desired, i.e. to the extent necessary to effect a bending operation of one side of the clip, pin 40 riding on cam surface 39 of linkage 32 causes surface 38 to be just barely engaging pin 36.

Upon further motion of handles 15 and 16 toward one another (see Figure 2C), pin 40 forces linkage 32 to move underneath pin 36 thereby disengaging linkage 32 from said pin 36. Spring 29 will then operate to snap bracket 27 back out of the way in a counterclockwise direction about pivot point 28, with pin 36 of arm 31 then riding on the upper surface of linkage 32. Further depression of handles 15 and 16 toward one another will therefore have no effect on the movement of bending jaw 25 since there is no driving engagement between linkage 32 and pin 36; and bending jaw 25 will be caused to remain at its quiescent position away from socket 23. As the handles 15 and 16 are fully depressed, bending jaw 19 slides across the upper portion of socket 23 to effect a second bending operation, i.e. the bending of the second portion or leg of the clip over the first portion already bent; and it will be noted that this second bending operation effected by jaw 19 is done free of interference from bending jaw 25.

Upon release of pressure on handles 15 and 16, spring 24 will cause those handles to move apart, whereafter spring wire 34 will lift linkage 32 back in the position shown in Figure 2A preparatory to a further clipping operation; and the bundle of wires having the wrapped clip thereabout can then be readily removed from the socket 23.

Summarizing the operation described, therefore, it will be noted that a wrapped clip is effected by a simple depression or squeezing of the handles 15 and 16 toward one another. This simple motion causes one bending jaw to pivot into bending position adjacent a work location at a time when the other bending jaw is relatively remote from said work location; and as the handles of the pliers type tool are continuously moved toward one another, the first jaw snaps away from the work location to permit a subsequent bending operation by the other jaw. In actual practice, therefore, a wrapped clip may be formed by the simple expedient of squeezing the handles of a pliers type tool toward one another; and this simple continuous squeezing motion automatically effects a complex motion of at least one bending head to cause that head to engage a clip and then move out of the way to

permit subsequent engagement of the clip by the other head.

It will be appreciated that, during the clipping operation, the bundle of wires itself acts as a form about which the clip is wrapped and, in actual practice various numbers of wires may have to be bundled to one another. It is particularly contemplated that anywhere from two to ten wires can be clipped together by the mechanism of the present invention. Adjustment means are provided in order to permit the operator of the tool to bundle any desired number of wires together. In particular, adaptor means are associated with socket 23, forming a movable floor for said socket whereby, as the number of wires to be clipped decreases, the floor of said socket may be moved upwardly to accommodate a lesser number of wires, with the resulting bundle of wires still being arranged so that the uppermost wires are adjacent the top of socket 23 to permit the clip to be bent around the wires, over the top of that socket, and onto the top of the bundle of wires in the manner described. To this effect (see Figures 3 and 4), the adaptor comprises an elongated bar 45 of L-shape, having a portion 45a extending into and across the bottom of socket 23. Adaptor bar 45 includes an elongated slot 46 cooperating with a knurled set screw 47 extending through said slot 46 into thread engagement with head 22. By simply loosening and thereafter tightening set screw 47, the adaptor 45 may be moved upwardly and downwardly, as illustrated by dotted lines 48 in Figure 3, to permit clips of various sizes and/or different numbers of wires to be received by socket 23.

While I have thus described a preferred embodiment of the present invention, it must be emphasized that the foregoing description is meant to be illustrative only, and should not be considered limitative of my invention. Various modifications will be suggested to those skilled in the art; and in particular, various alternative mechanical arrangements operating generally in accordance with the principles already described, can be effected. All such variations and modifications as are in accord with the principles of the present invention are therefore meant to fall within the scope of the appended claims.

Having thus described my invention, I claim:

1. A pliers type tool adapted to wrap a clip about a bundle of wires, comprising a pair of operating handles pivoted to one another at a point between the ends thereof, a pair of bending jaws connected to corresponding first ends of said pair of handles whereby manual movement of the other ends of said handles toward and away from one another effects similar movement of said first ends relative to one another, at least one of said bending jaws being pivotally connected to one of said handles, and means responsive to movement of said handles toward one another for causing said one bending jaw to initially pivot on said one handle toward said other handle and thereafter away from said other handle as said handles are continuously moved toward one another.

2. The combination of claim 1 wherein said responsive means includes resilient means engaging said one bending jaw for normally urging said one jaw away from said other handle, linkage means extending between said one jaw and said other handle for moving said one jaw toward said other handle against the restraint of said resilient means, and means for rendering said linkage means inoperative after said handles have moved toward one another beyond a predetermined point whereby said resilient means thereafter operates to move said one jaw away from said other handle.

3. The combination of claim 1 including a projection on said one jaw, said responsive means comprising linkage means extending from said other arm to removably engage said projection whereby movement of said handles toward one another initially causes said linkage means to effect pivotal movement of said one jaw, and means for disengaging said linkage means from said projection after

said handles have passed a predetermined point in their movement toward one another.

4. The combination of claim 1 including a socket on said tool adapted to receive a clip to be bent, said socket being located at a position between said bending jaws whereby said one jaw moves toward and thereafter away from said socket while the other jaw is relatively remote from said socket, whereafter said other bending jaw moves to a position closely adjacent said socket upon continuous movement of said handles toward one another.

5. The combination of claim 4 including resilient means on said tool adjacent said socket for resiliently retaining a clip within said socket.

6. A pliers type bending tool comprising a pair of arms pivotally connected to one another at a position between the ends thereof, a pair of bending jaws connected to corresponding ends of said arms, an open-ended socket on said tool adapted to receive a structure to be bent, and means responsive to continued movement of said arms toward one another about said pivotal connection for causing one of said jaws to move toward and thereafter away from the open end of said socket as the other of said jaws moves continuously toward said socket whereby said one jaw is adapted to effect an initial bending operation and said other jaw is adapted to effect a subsequent bending operation free of interference from said one jaw.

7. A readily portable manually operable bending tool comprising means defining a work location adapted to receive a device to be bent, a pair of bending jaws mounted on opposite sides of said work location, and hand operable operator means mechanically connected to both said jaws for simultaneously moving said jaws toward said work location, said operator means including means for causing one of said jaws to move toward said work location at a more rapid rate than the other of said jaws whereby said one jaw is adapted to effect a bending operation at said work location in advance of a subsequent bending operation effected at said work location by the other of said jaws.

8. A bending tool comprising means defining a socket adapted to receive a device to be bent, a first bending jaw movably disposed adjacent one side of said socket, a second bending jaw movably disposed adjacent the other side of said socket, means for moving said second bending jaw toward said socket, linkage means extending from said second bending jaw to said first bending jaw and removably engaging said first jaw for moving said first bending jaw toward said socket in response to movement of said second bending jaw toward said socket, said linkage means moving said first jaw into a bending position at said socket while said second jaw is remote from said socket, means responsive to movement of said second jaw toward said socket beyond a predetermined position for disengaging said linkage means from said first jaw while said second jaw is still remote from said socket, and spring means coupled to said first jaw for moving said first jaw away from said socket upon disengagement of said linkage means thereby to permit said second jaw to move into a bending position at said socket.

9. The combination of claim 8 wherein said first jaw is pivotally mounted on said socket defining means, a first projection on said first jaw adapted to removably engage said linkage means, said linkage means including a cam surface, and a second projection extending from said socket defining means adjacent said cam surface for moving said linkage means to a position of disengagement with said first projection at said predetermined position of movement of said second jaw.

10. A pliers type tool having a pair of handles adapted to be manually pressed toward one another about a pivot connecting said handles, a block forming a unitary portion of one of said handles on one side of said pivot,

said block including a recess adapted to receive work to be operated upon by said tool, a bracket pivotally attached to said block at one side of said recess, said bracket including a first jaw extending toward said recess and normally remote therefrom, a second jaw normally remote from said recess and extending from the other of said handles toward said recess at the other side of said recess, a linkage element movably attached to said other of said handles and extending into removable engagement with said bracket, whereby partial manual pressing of said handles toward one another causes said linkage element to pivot said bracket about its pivot point on said block thereby to move said first jaw to a position adjacent said recess while said second jaw is still remote from said recess, and means extending from said block and engaging said linkage element for moving said linkage element out of engagement with said bracket upon further manual pressing of said handles toward one another thereby to permit said second jaw to move to a position adjacent said recess unimpeded by said first jaw. 20

11. The combination of claim 10 wherein said bracket includes a pin extending therefrom, said linkage element including a latching portion engaging said pin.

12. The combination of claim 10 wherein said linkage element is pivotally attached to said other handle, 25 and spring means extending between said linkage ele-

ment and said other handle for normally urging said linkage element into engagement with said bracket.

13. The combination of claim 12 wherein said linkage element includes an elongated edge extending past said block, said means extending from said block and engaging said linkage element comprising a pin extending from said block and riding on said elongated edge during at least a portion of the movement of said linkage element relative to said block.

14. The combination of claim 10 including adaptor means movably disposed in said recess for varying the effective size of said recess.

15. The combination of claim 10 including spring means attached to said bracket and normally urging said first jaw away from said recess whereby said spring means is operative, when said linkage element is moved out of engagement with said bracket, to move said first jaw away from said recess.
